UNITED STATES PATENT OFFICE

153,327

DESIGN FOR FOOD TONGS

Alfred E. Taylor and John D. Coleman, Detroit,
Mich.; said Coleman assignor to said Taylor

Application April 9, 1947, Serial No. 138,266

Term of patent 14 years

(CL. D44—4)

To all whom it may concern:

Be it known that we, Alfred E. Taylor and John D. Coleman, citizens of the United States, residing in Detroit, in the county of Wayne and State of Michigan, have invented a new, original, and ornamental Design for Food Tongs, of which the following is a specification, reference being had to the accompanying drawing, forming a part thereof, wherein

Fig. 1 is a perspective view of the food tongs in partially open position, showing our new design.

Fig. 2 is a top view of the food tongs.

Fig. 3 is a side view of the food tongs shown in fully closed position, and

Fig. 4 is an end view of the tongs shown in fully closed position.

We claim:

The ornamental design for food tongs, substantially as shown.

ALFRED E. TAYLOR.
JOHN D. COLEMAN.
